St. Louis, Mo., a corporation of Missouri

Application January 20, 1936, Serial No. 59,874

17 Claims.

(Cl. 229—55)

This invention relates to bags generally, and with regard to certain more specific features, to multiply, paper bags.

Among the several objects of the invention 5 may be noted the provision of means for providing a full mouth opening for filling purposes and at the same time providing for a predetermined conformation of closure of the bag mouth after filling; the provision of means for obtaining 10 said predetermined conformation of closure by a simple set of manipulations; the provision of a bag of the class described which has all of the means for attaining the said ends located out of sight between the plies of the bag so as to present 15 a smooth exterior and a smooth interior; the provision of a bag of the class described which presents a neat appearance after ultimate closure; and the provision of a bag of this class which is simple and economical to manufacture. Other 20 objects will be in part obvious and in part pointed out hereinafter.

The invention accordingly comprises the elements and combinations of elements, features of construction, and arrangements of parts which 25 will be exemplified in the structures hereinafter described, and the scope of the application of which will be indicated in the following claims.

In the accompanying drawings, in which are 30 illustrated several of various possible embodiments of the invention,

Fig. 1 is a perspective view showing the application to a gusseted bag of one form of the invention;

Fig. 2 is another perspective view of the bag 35 mouth of Fig. 1 showing the same in more extended position for filling;

Fig. 3 is a cross section taken on line 3—3 of Fig. 2, diagrammatically illustrated;

Fig. 4 is a fragmentary view similar to Fig. 2 40 showing a folding manipulation upon a filled bag;

Fig. 5 is a view similar to Fig. 4 showing the ultimate appearance of the corner of a filled and closed bag;

Fig. 6 is a view similar to Fig. 2 showing a modified conformation of the invention per se;

Fig. 7 is a view similar to Fig. 4 but referring to the Fig. 6 form of the invention;

Fig. 8 is a view similar to Fig. 5 but referring to the Fig. 6 form of the invention;

Fig. 9 is a perspective view of the invention 50 applied to a non-gusseted bag;

Fig. 10 is a view similar to Fig. 4 but illustrating the non-gusseted bag;

Fig. 11 is a view similar to Fig. 5 but illustrating 55 the non-gusseted bag;

Fig. 12 is a side elevation of a flatly folded blank of another bag showing another form of the invention, parts being broken away;

Fig. 13 is a perspective view of the Fig. 12 form of the invention, showing a filled bag after a 5 first closing step;

Fig. 14 is a view similar to Fig. 13 showing a second closing step;

Fig. 15 is a view similar to Fig. 13 showing a 10 third closing step; and,

Fig. 16 is a view similar to Fig. 13 illustrating a fourth closing step and the final appearance of 15 the Fig. 12 form of bag.

Similar reference characters indicate corresponding parts throughout the several views of 15 the drawings.

In both gusseted and non-gusseted bags, particularly of the multi-ply paper variety, closure difficulties have been encountered after filling. This difficulty has been caused by the fact that 20 upon filling, the edges of the bag bulge outwardly, and this bulging effect extends to the ends of the mouth of the bag. Thereafter, it becomes difficult to properly manipulate the more or less constrained mouth to provide, without crumpling, 25 the proper folds for obtaining the type of closure desired.

A solution to the above problem has been suggested, namely, to clip the mouth of the bag at the ends to hold the gusset or the like, and so 30 to prevent disarrangement of the same. This constricts the bag mouth so that filling is hindered and it requires an unsightly, extraneous clip or the like, which interferes with closure seaming and, unless the clip is torn from the bag 35 by the user, it interferes with pouring from the mouth. These clips also may loosen and enter the product in the bag. The present invention provides for a maximum bag mouth opening during filling and emptying, and provides a ready 40 and quick means for effecting a neat closure for various classes of bags.

Referring now more particularly to Fig. 1, there is shown generally at numeral 1 a multi-ply paper bag of the gusseted variety. The faces of the 45 bag are illustrated at numerals 3 and the gussets generally at numerals 5, each gusset 5 comprising panels 7 respectively hinged to the respective faces 3 of the bag at the creases 9, and hinged to one another at the creases 11. Thus a 50 bellows-like, expandible construction is obtained.

The bag comprises four laminations of paper 55 13 which are generally free of one another throughout substantially the entire juxtaposed areas. In effect, each multi-ply paper bag is a

composite of four paper bags, one arranged inside of another. The advantages of such bags are known. Other numbers of plies may also be used.

5 In order to carry out the invention, we provide between adjacent plies, limited, predeterminedly shaped areas of adhesive, spaced from one another or equivalently related to one another for the purpose of constraining the region about the 10 mouth of the bag to flex along predeterminate lines, instead of flexing by indeterminate crumpling. For instance, as illustrated in Figs. 2 and 3, triangular areas of adhesive 15 are positioned to adhere to adjacent plies. In a given area, 15 there are three layers of adhesive integrating the four juxtaposed layers of paper. However, each triangle of adhesive has a limited area and a definite shape which corresponds to the shape of the area of adhesive between adjacent plies. The 20 areas 15 are spaced to permit flexing at crease 11. At 17 is illustrated another group of juxtaposed, triangular adhesive areas between adjacent plies. These are spaced from one another to permit flexing at said crease 11, also at creases 25 9, and provide for subsequent bending or creasing along lines 23 (Figs. 2 and 5).

At 19 are juxtaposed areas of adhesive between adjacent plies of paper. These are spaced from areas 17 to provide for flexing at crease 9. At 30 21 is illustrated another group of adhesive areas.

As illustrated in Figs. 1 and 2, the areas of adhesive maintain the integrated areas of paper relatively stiff but they do not interfere with the free opening of the bag from the Fig. 1 position to that shown in Fig. 2 (by flexing along folds 35 9 and 11), whereupon it may be filled. Filling is accomplished to a level approximately up to the lower edges L of the adhesive area 15, 19.

Then, by pressing at about point P (see Figs. 40 2 and 4) the parts of the gusset 5 adjacent the mouth of the bag may readily be pushed inwardly. This is because the relatively rigid areas obtained by interposing the adhesive are spaced from one another to provide for free folding 45 along folds 9, 11 and along lines 23 and L. The relatively rigid areas of adhesive do not crumple and thus they predetermine the folding action.

It is to be understood that corresponding operations (illustrated in Fig. 4) take place on opposite ends of the mouth of the bag. Thereafter the edges 31 of the bag mouth become positioned adjacent one another. A closure tape 33 is then applied thereover and either with or without adhesive, is sewed along the line 35. Downward pressure then results in a free fold along the line 37, as determined by the upper edges of the adhesive areas 19 and 21. The fold L on the bag sides and corners is thus also determined.

From the above, it will be seen that the invention provides for relatively stiff, hinged invisible panels which permit of free opening of the bag mouth for filling and easy collapsing of the same without crumpling, but along definite lines of folding, which simplifies the closing operation and ultimately presents a much neater appearance. It should be noted that although a limited length of lower edge 39 is provided on each panel 19 in order to localize the three-way bend at each corner 41, said edge 39 may be extended 70 across the width of the bag by extending down the panels 21, thus to more positively determine a crosswise fold parallel to fold 37.

In Fig. 6 is shown the same type of bag as shown in Figs. 1 to 5, but the areas of adhesive 75 between paper plies are shaped as a pair of rec-

tangles 43 in each panel 7 of each gusset 5, and a pair of rectangles 45 are used in the sides 3 of the bag wall and spaced from the pairs 43. The rectangles of adhesive 21 are retained.

After filling the Fig. 6 form of bag, it is formed as shown in Fig. 7 by pressing from opposite ends of the mouth, whereupon the folds 9 and 11 are determined; also fold L. There is no diagonal fold corresponding to the fold 23 in the first form of the invention, but the rectangles being separate thin strips, vertically arranged, tend to curl freely as shown at 2 (Fig. 8).

Figs. 9 to 11 show the adhesive-area conformations of Figs. 1 to 5 applied to a non-gusseted bag. In this class of bag, there is only one original fold 11 on each bag edge, and no folds corresponding to those shown at 9 in Fig. 1. Similar reference characters indicate corresponding parts.

The operation of this Fig. 9 to 11 bag is in general similar to that shown in Figs. 1 to 8 and 20 is different only in particulars. This bag mouth is opened for filling, and thereafter, upon endwise pressure at the mouth, the mouth may be closed as shown in Figs. 10 and 11. The chief difference is that areas 17 and 19 determine a 25 new fold, instead of only freely permitting flexing of a fold such as 9 in Figs. 1-5.

The invention is quite as useful on the non-gusseted bags as it is upon the gusseted ones, 30 for it provides for stiff panels which prevent indeterminate crumpling and provides for determinate relationships between areas.

In Figs. 12 to 16 is shown another form of non-gusseted bag in which the adhesive areas are distributed as follows:

Rectangular adhesive areas 55 are placed adjacent one another on opposite sides of the empty bag with their inner edges spaced to permit of folding at lines 11 when the bag is opened. Their outer edges permit of folding at lines 59 and 40 adjacent the said lines 59 are quadrilateral adhesive areas 61, which with the spaced triangular adhesive area 63 on each side of the bag, leave adhesive-free notches 65 at the centers of the upper edges of the bag. The adhesive-free 45 notches at 65 provide for folding functions to be described. The operation of the closure of the Figs. 12 to 16 form of the invention is illustrated in Figs. 13 to 16, and is as follows:

The bag having been filled to near the level at 50 line L, one edge of the open mouth is pushed down by pressing the two rectangles 55 as shown in Fig. 13. Folding is along lines L and 59. Second, the opposite two rectangles 55 are pressed down as shown in Fig. 14. It will be seen that in order to fold down the second two rectangles there should be the adhesive-free notches 65.

Next, one triangular side area 63 is folded down as shown in Fig. 15, and then as shown in Fig. 16, the other triangular side flap 63 is folded down. The closure may be held shut by suitably applying adhesive, or by tying or otherwise.

It will be understood that the exact method of holding the bag shut after closure is not the gist of the present invention. The invention refers to the provision of a plurality of spaced or equivalently related, stiffened areas by means of which is provided a predetermined conformation upon closure, and by means of which said closure is effected upon predetermined lines, rather than by an indeterminate crumpling.

It is to be further understood that the number of plies is inconsequential, four being generally used, but that the invention is applicable to two- 75

ply bags and others. Furthermore, it is applicable not only to multi-ply paper bags, but also to multi-ply fabric bags or multi-ply fabric and paper bags.

5 It is also to be understood that adhesive areas may be used in between a number of pairs of plies less than the whole number of pairs of plies used. For instance, in a four-ply bag, only two layers of adhesive may be used, rather than three 10 as shown in Fig. 3. Such a form would partake of most of the advantages of the invention, although the best results are obtained by adhering all plies over a given area.

15 The invention is also useful, but to a smaller degree, on a single-ply bag, by applying areas of adhesive as outlined herein, either inside or outside of the bag. This provides the advantages of predetermined shaping of the bag upon closing, although there are the disadvantages that the 20 adhesive areas will be exposed if placed on the outside of the bag, or will come into contact with the contained goods if placed on the inside.

25 It will be noted that in the forms of the invention shown in Figs. 1 to 11, the final form of the closure for the mouth of the bag is sloping with an upper seal and intucks at the ends of the seal. In all forms no distortion extends below the 30 lowermost edges of the groups of adhesive areas and there is a clean-cut demarcation between the top and sides and ends of the bag.

35 It is clear from the above that the invention applies to bags such as shown in Figs. 1-11 when the tape 33 is omitted and the stitching 35 only used for closure.

3. In view of the above, it will be seen that the several objects of the invention are achieved and other advantageous results attained.

40 As many changes could be made in carrying out the above constructions without departing from the scope of the invention, it is intended that all matter contained in the above description or shown in the accompanying drawings shall be interpreted as illustrative and not in a limiting sense.

45 We claim:

1. In a multi-ply bag, predetermined areas of stiffening material between at least some adjacent plies adapted to limit any substantial distortion to regions adjacent the said areas, said areas having such a form and being so positioned and related that after filling of the bag, the subsequently formed closure thereon takes a form consisting of substantially predetermined outline.

2. In a multi-ply bag, a plurality of areas of adhesive located between at least two adjacent plies, said areas having edges at a common distance from the mouth of the bag, and a plurality of said areas having a common lower level near the edges of the bag and all areas being so spaced 60 from one another so that upon closure of the bag mouth, a sloping-topped closure is obtained with predetermined intucks at the ends thereof.

3. In a multi-ply bag having folded edges, a plurality of spaced areas of adhesive between at 65 least two plies, all of said areas having upper edges spaced at a common distance from the mouth, and adjacent areas being spaced from one another at said bag edges to provide for free opening of said mouth at the folded edges, said adhesive areas permitting free closure of said mouth along a predetermined conformation after filling of the bag.

4. A multi-ply bag having a mouth and edge 70 folds, comprising a plurality of spaced areas of

adhesive between at least two plies, the upper edges of said areas having a common distance from the mouth, and adjacent areas at the edge folds being spaced to permit free hinging along the folds whereby the bag may readily be opened 5 and closed at the mouth, and said areas adjacent the folds having other linear spacings to provide for predeterminedly free intucking after filling and before closure.

5. A multi-ply bag having gusset-forming 10 folds, comprising a plurality of spaced areas of adhesive between at least two plies, the upper edges of said areas having a common distance from the edge of the mouth of the bag, and adjacent areas at the gussets being spaced to permit free hinging along the gusset folds whereby 15 the bag may readily be opened and closed, and said areas adjacent the gusset-folds having linear spacings therebetween to provide for free intucking after filling and before closure. 20

6. A bag having an open mouth and pre-folded edges, means for readily closing said mouth after filling of the bag comprising a plurality of stiffened regions adjacent said mouth and at each edge, said stiffened regions being spaced from one 25 another to predeterminedly confine flexing along lines including portions of said edges.

7. A bag having an open mouth and pre-folded edges, gussets at said edges, means for readily closing said mouth after filling of the bag comprising a plurality of stiffened regions in said gussets, said stiffened regions being spaced from one another to predeterminedly confine flexing along lines including portions of said edges. 30

8. In a multi-ply paper bag having creased side 35 gussets and a mouth, predeterminedly shaped and spaced areas of adhesive between at least some plies, said adhesive areas being spaced from one another along lines at the creases of the gussets, and along other lines providing for predetermined conformation of parts upon closure of said mouth to provide predetermined endwise intucks. 40

9. In a multi-ply paper bag having creased side 45 gussets and a mouth, predeterminedly shaped and spaced areas of adhesive between at least some plies, said adhesive areas being spaced from one another at the creases of the gussets, and along diagonal lines providing for predetermined conformation of parts upon closure of 50 said mouth to provide predetermined endwise fully-folded intucks.

10. In a multi-ply bag having side gussets, said 55 gussets being articulated each at three creases and the bag having an open mouth, a plurality of spaced areas of adhesive between at least two plies of the bag, said areas limiting conformation of the bag mouth upon closure to definite lines including said creases.

11. In a multi-ply bag having side folds, said 60 folds being at each side of the bag and the bag having an open mouth, a plurality of spaced areas of adhesive between at least two plies of the bag, said areas limiting conformation of the bag mouth upon closure to definite lines including said creases. 65

12. In a multi-ply bag having side gussets, said 70 gussets being articulated each at three creases and the bag having an open mouth, a plurality of spaced areas of adhesive between at least two plies of the bag, said areas limiting conformation of the bag upon closure to lines including said creases, said adhesive areas being spaced peripherally around the mouth of the bag and having upper edges spaced endwise from the mouth to 75

provide for a predetermined closed-mouth conformation consisting of a hip shape and intucked ends.

13. In a multi-ply bag having side folds, said folds forming edge articulations, the bag having an open mouth, a plurality of spaced areas of adhesive between at least two plies of the bag, said areas limiting conformation of the bag upon closure to lines including said folds, said adhesive areas being spaced peripherally around the mouth of the bag and being all shaped as rectangles.

14. In a multi-ply bag having side folds, said folds forming edge articulations, the bag having an open mouth, a plurality of spaced areas of adhesive between at least two plies of the bag, said areas limiting conformation of the bag upon closure to lines including said folds, said adhesive areas being spaced peripherally around the mouth of the bag and being all shaped as rectangles, those near the side folds being vertically positioned and the others being horizontally positioned.

15. In a multi-ply bag having side folds and an open mouth, a plurality of spaced areas of adhesive between at least two plies of the bag, said areas limiting conformation of the bag up-

on closure to lines including said creases, said adhesive areas being spaced peripherally around the mouth of the bag to provide for a predetermined closed-mouth conformation, the areas adjacent the folds being rectangular.

16. In a multi-ply bag having side folds and an open mouth, a plurality of spaced areas of adhesive between at least two plies of the bag, said areas limiting conformation of the bag upon closure to lines including said creases, said adhesive areas being spaced peripherally around the mouth of the bag to provide for a predetermined closed-mouth conformation, the areas adjacent the folds being rectangular, and the others non-rectangular.

17. A multi-ply bag comprising relatively flexible individual plies, predetermined areas of stiffening adhesive between at least two plies of the bag, said areas having predetermined shapes and flexible spaces therebetween providing for a predetermined shape of at least part of the bag after filling, said shape comprising substantially plane areas joined at corners determined by said spaces.
